UNITED STATES PATENT OFFICE.

ORA E. STEGALL, OF RICHMOND, INDIANA, ASSIGNOR OF ONE-HALF TO GEORGE C. BALLINGER, OF RICHMOND, INDIANA.

AUTOMATIC GRAVE COVER.

Application filed October 11, 1923. Serial No. 667,785.

To all whom it may concern:

Be it known that I, ORA E. STEGALL, a citizen of the United States, residing in the city of Richmond, in the county of Wayne, State of Indiana, have invented a new and useful Automatic Grave Cover, of which the following is a full, clear, and comprehensive specification and exposition, the same being such as will enable others to make and use the same with exactitude.

The object of my present invention, broadly speaking, is to provide a device adapted to contribute to minimizing the dread or consternation one feels before an open grave as the body of one's friend is being lowered thereinto, and to make the conditions and the remembrances thereof as pleasant as possible.

Another object is to provide a construction adapted to automatically operate in connection with a casket lowering device and adapted to carry floral offerings or other remembrances, with means whereby as the casket moves downward into the grave my invention will automatically, silently, and slowly move over and cover and close the grave opening, whereby the floral offerings alone will be in view, and thereby making the conditions more pleasant.

My invention is simple in character, strong and durable in construction, easily operated and controlled, automatic in its movements, easily and quickly assembled or taken apart, requiring only a minimum of space for its storage or transportation, will not interfere with the usual operations of placing a casket in position or lowering it into a grave, providing an artistic ensemble when in use, and which can be manufactured and sold at a comparatively low price.

Other minor objects and particular advantages of the invention will suggest themselves in the course of the following description and that which is new will be correlated in the appended claims.

One manner of carrying out the principles of my invention in a practical way is shown in the accompanying three-sheets of drawings, forming part of this specification, in which—Figure 1 is a top plan view of my invention, in connection with a casket lowering device, and a casket in position at the commencement of its movement being lowered into a grave. Figure 2 is a plan view

of the same, with the casket shown in position wherein it has moved downward just below the surface of the ground. Figure 3 is an end elevation of the same, wherein the casket has reached the bottom of the grave, with my device directly over the grave in its final operative position. Figure 4 is a top plan view of a portion of the lowering device, showing the auxiliary tracks fully extended parallel with each other, with their free ends resting on the outer roller of the lowering device. Figure 5 is a vertical section of one of the two supporting posts, showing portions of the tracks in connection therewith. Figure 6 is a plan view of one of the two auxiliary frames or wings, showing the manner of their connection. And Figure 7 is an enlarged detail side elevation of one of the automatic release devices.

Similar indices denote like parts throughout the several views.

In order that the construction, the objects, and the several advantages of the invention may be more fully understood and appreciated I will now take up a detailed description thereof, in which I will set forth the same as fully and as comprehensively as I may.

The parts shown in the drawings which are well known and form no part of my invention, but are merely shown to make clear the operation thereof when associated therewith, are denoted by letters; while the parts which are new and form my invention are denoted by numerals.

In the drawings letter A denotes a grave and B denotes the surface of the earth in which the grave is formed.

Letter C denotes a burial casket, to be lowered into the grave A in the usual manner.

For lowering the casket it is usual to employ a lowering-device, comprising the end members D and E, and the revolvable side members or rollers F and G, the ends of the side members turning in the corner members or housings H, I, J and K where they are geared to revolve synchronously, controlled by the lever L. The ends of the end members D and E are secured in the respective corner members.

Letter M denotes run-boards, forming a frame resting on the surface B, and sur-

rounding the grave A, and on which the lowering device is supported, and it provides walk-ways for the pall-bearers when placing the casket on the lowering device.

5 Letter N denotes the two lowering straps, whose ends are connected to the rollers F and G and they are adapted to be rolled thereon. Said rollers always turning in directions opposite to each other.

10 The invention proper comprises a relatively stationary frame, consisting, first, of two body posts 1 and 2, as shown in Fig. 5, each having a flanged base to rest on the ground B, each having a vertical socket 3 (shown only in Fig. 5) which extends downward through their upper ends, each having a horizontal aperture 4 therethrough near their lower ends; each having a rearwardly extending pintle 5 at its upper end; and each 20 having a bracket 6, whose face is directly below the pintle 5 with a channel formed in said face concentric with the pintle 5, for the purpose hereinafter stated.

Said posts 1 and 2 are detachably connected by the front tie-rod 7, whose end portions are disposed through the openings 4 of the posts 1 and 2, where they may be rigidly secured by the respective thumb-screws 8, after said posts are properly spaced, and 30 said tie-rod not only prevents said posts from moving laterally with relation to each other but it prevents them from turning.

Numerals 9 and 10 denote the relatively fixed track-rails, each adapted to fit in its respective channel formed in the upper face of the brackets 6, and having openings in their forward ends in which may fit the respective pintles 5 whereby the rails 9 and 10 will be rigidly but detachably connected with 40 the posts 1 and 2. The rear ends of the rails 9 and 10 are threaded into the respective fittings 11 and 12, and said fittings are connected by the tie-rod 13 which extends therebetween.

45 Numerals 14 and 15 denote the adjustable standards, which are slidably mounted through the respective fittings 11 and 12, and each is adapted to be secured at any point by the respective set-screw stops 16 and 50 17. The lower ends of each of the standards 14 and 15 is provided with a disc foot 18, as in Fig. 3, to rest on the surface B, or the lower ends of said standards may be formed pointed whereby they may be driven into 55 the ground.

By loosening the stops 16 and 17 it is evident that the standards 14 and 15 may be raised and lowered, in order to level the tracks 9 and 10, regardless of the inclination 60 of the surface B.

The upper ends of the standards 14 and 15 may be provided with balls, flags, or other decorative finish as desired.

The stationary frame thus formed is to 65 be assembled near one side of the grave A,

with the posts 1 and 2 near the run-board M of that side, as shown.

The swinging track members 19 and 20 are formed with one end portion of each turned at right-angles thereto, as the part 21 shown 70 in Fig. 5. The parts 21 are adapted to fit and turn in the respective sockets 3 of the posts 1 and 2, whereby said tracks 19 and 20 may swing horizontally to and from the 75 positions shown in the drawings, being located as in Fig. 1 when the device is first assembled in operative position.

The carriage consists essentially of two main sections, which are identical with each other; and two wing sections, which are 80 identical with each other; the whole forming a rectangular table or platform, which I will now described in detail: One of the main sections of the carriage comprises the front and the rear rods, 22 and 23 respectively, which are parallel with each other, and two side rods 24 and 25, which are also parallel with each other. The rods 22 and 25 are connected by the T-fitting 26. The rods 25 and 23 are connected by the T-fit- 90 ting 27. The rods 23 and 24 are connected by the T-fitting 28. And the rods 24 and 22 are connected by the T-fitting 29. The frame section thus formed is covered by a sheet of aluminum 38, or other metal, or with 95 fabric or wood, or other material may be employed whereby a table top is provided.

The other main section of the carriage comprises the front and the rear rods 30 and 31, respectively, which are parallel with 100 each other, and the two side rods 32 and 33 also parallel with each other. The rods 30 and 33 are connected by the T-fitting 34. The rods 33 and 31 are connected by the T-fitting 35. The rods 31 and 32 are connected by the T-fitting 36. And the rods 32 and 30 are connected by the T-fitting 37. The said 105 second frame is covered by a sheet of aluminum 39, or other material the same as the first section.

The said main sections are adapted to be detachably connected by the dowels 40 and 41, the former projecting from the fitting 35 in which it is fixed and is adapted to be removably inserted in the fitting 26 (Fig. 6); while the latter projects from the fitting 36 in which it is fixed and adapted to be removably inserted in the fitting 27.

One wing of the carriage comprises the rod 42, of same length as the rod 24 with 120 which it is parallel, and it has the L-fittings 43 and 44 on its ends. Said fittings 43 and 44 carry the short rods 45 and 46, respectively, which are parallel with each other and at right angles to the rod 42. The free ends of the short rods 45 and 46 are adapted to be detachably inserted in the respective fittings 29 and 28. And this wing is covered by a sheet of aluminum 80, or the like.

The other wing of the carriage comprises 130

the rod 49, of same length as the rod 33 with which it is parallel, and it has the L-fittings 50 and 51 on its ends. Said fittings 50 and 51 carry the short rods 52 and 53, respectively, which are parallel with each other and are at right angles to the rod 49. The free ends of the short rods 52 and 53 are adapted to be detachably inserted in the respective fittings 37 and 36, and this wing 10 of the carriage is covered by a sheet of aluminum 81, or the like.

Extending across between the rods 22 and 23, and secured thereto, as by the bolts 54 and 55, is the bar 56, which is located a short 15 distance from and parallel with the rod 24. Likewise extending across between the rods 30 and 31, secured thereto, as by the bolts 57 and 58, is the bar 59, which is located a short distance from and parallel with the 20 rod 33.

Said bars 56 and 59 are located directly above the respective rails 9 and 10.

Secured to the bar 56, as by the bolts 60 and 61, are respective forward and rearward 25 brackets (not shown) which extend down from the underside of said bar, each carries a track-wheel (not shown) which wheels are adapted to travel on the tracks 9 and 19, in the same manner as that shown at the right 30 in Fig. 3.

Likewise secured to the bar 59, as by the bolts 62 and 63, are the respective forward and rearward brackets 64 and 65, which extend downward from the underside of said 35 bar, as shown in Fig. 3. The brackets 64 and 65 carry the respective track-wheels 66 and 67, which are adapted to travel on the tracks 10 and 20.

All of said track-wheels are formed with 40 inwardly curved or concave faces, whereby they will stride the respective tracks without danger of inadvertently coming off.

Numerals 68 and 69 denote curved fingers 45 which extend downward and inward from the respective bars 56 and 59 to which they are secured, and they are adapted to engage the respective track members 19 and 20, as shown in Fig. 2.

50 Detachably secured around the roller F are split pulleys 70 and 71, on which are adapted to be wound the respective straps 72 and 73, with their inner ends secured thereto.

Secured on the outer, rear, ends of the 55 respective straps 72 and 73 are the respective links 74 and 75.

Secured to the rear portion of the carriage, as for instance to the rods 46 and 53 (or if preferred to the rods 23 and 31) but in 60 line with the pulleys 70 and 71, are the curved catches 76 and 77, each of which has a latch, 78 and 79 respectively, formed of comparatively small spring wire, in connection therewith to hold the links 74 and 75 in 65 connection with the hook portions of the

catches, as in Fig. 7, until the rear edge of the carriage is almost over the roller F, when the downward pull, caused by the links turning to the position shown by dotted lines in Fig. 7, will cause the links to pull free 70 of the latches and thereby stop the travel of the carriage.

The operation of my invention is substantially as follows:

After the grave has been excavated the 75 run-boards M are placed therearound on the ground B. The lowering device is then set up upon the run-boards and surrounding the grave, the straps N being made taut. After which my device is set up at one side of the 80 grave as shown, with the posts 1 and 2 near the run-board, adjusting the height of the posts whereby the auxiliary tracks 19 and 20 will be at a slightly higher elevation than the top of the lowering device, but at this 85 time each of said auxiliary tracks should be folded inward, as in Fig. 1. The standards 14 and 15 should be adjusted whereby the tracks 9 and 10 will be substantially level. 90

The carriage is next placed upon the tracks 9 and 10 and located far enough to the rear where it will not interfere with persons walking around the grave.

The straps 72 and 73 are next extended 95 under the carriage from their pulleys 70 and 71, and the links 74 and 75 are then engaged in their respective catches 76 and 77.

If desired, a fabric spread, either plain or ornamental, (not shown) may be placed over 100 the entire table or carriage, with its edges extending or hanging down therearound, after which flowers and other decorations or remembrances may be placed thereon.

The casket C may now be placed upon the 105 strips N where it will be supported thereby.

Now by a movement of the lever L the lowering device will operate, permitting the rollers F and G to turn, thereby unwinding the strips N therefrom and causing the casket to slowly move downward. 110

Now as the casket moves downward it is apparent that the straps 72 and 73 will wind around the pulleys 70 and 71, thereby drawing the carriage horizontally toward the 115 grave while the casket moves downward vertically into the grave.

Immediately after the top of the casket has come below the upper level of the lowering device the carriage will have moved forward whereby the fingers 68 and 69 will impinge the auxiliary track-members 19 and 20, and as the carriage continues to move forward the said auxiliary track members will be swung forward and outward and finally arriving in position parallel with the track members 9 and 10, and therefore as the carriage continues to move forward the wheels on which the carriage is mounted 120 will roll out on said auxiliary tracks, as 125 130

shown in Fig. 3. The weight of the carriage will cause the outer end portions of the tracks 19 and 20 to contact with the roller G, by which they will be supported.

5 As the carriage reaches the position in which it is shown in Fig. 3, that is directly over the grave, it is evident that the un-
wound end portions of the straps 72 and 73 will be pulled somewhat downward, instead
10 of directly forward or horizontal as at first, therefore at this point the links 74 and 75 will automatically be pulled out of their respective latches, thereby causing the carriage to stop at this point, however the casket will
15 continue to move downward until it reaches the bottom of the grave.

It is intended that the carriage and the flowers thereon shall remain over and covering the grave until the friends have departed, or it may be easily pushed back to its starting position.

20 From the above it is apparent that, when leaving, the last sight the friends will have will not be of the casket and the grave, but
25 in place thereof the last sight will be of the flowers which are displayed upon the table of the carriage, thereby accomplishing the object of the invention by providing an artistic ensemble long to be remembered by
30 the friends.

I desire that it be understood that various changes may be made in the several details of construction and the arrangement of parts from that herein shown without departing
35 from the spirit of the invention and without sacrificing any of the advantages thereof.

Having now fully shown and described my invention, what I claim and desire to secure by Letters Patent of the United
40 States, is—

1. An automatic grave covering comprising in combination with a grave, a casket and a casket lowering device; a horizontal table located at one side of the grave, and
45 means whereby as the casket is lowered into the grave said table will move horizontally and cover the grave opening.

2. An automatic grave covering comprising in combination with a grave, a casket, and a casket lowering device; a horizontal table located at one side of the grave, means whereby as the casket is lowered into the grave said table will move horizontally and cover the grave, and means by which when
55 the table reaches position directly over the grave it will stop and remain stationary

while the casket continues to be lowered in the grave.

3. An automatic grave cover, comprising a horizontal table, wheels connected to the table, relatively stationary tracks on which said wheels revolve, means for moving the table in one direction upon said tracks, auxiliary tracks which are normally turned at right angles to the stationary tracks, and means carried by the table for turning said auxiliary tracks into alinement with the stationary tracks whereby said wheels may travel from the stationary tracks onto the auxiliary tracks.

4. An automatic grave cover, comprising a carriage forming a table and formed by a plurality of frames, means for detachably connecting said frames, detachable wings for said frames, relatively stationary tracks for the carriage, wheels connecting the carriage with said tracks, foldable extension tracks, means carried by the carriage for turning the extension tracks whereby they will provide continuations of the first named tracks, and means for automatically drawing the carriage in one direction.

5. An automatic grave cover comprising in combination, a carriage forming a table, means for detachably connecting the various parts of the carriage, wheels for supporting the carriage, relatively stationary tracks on which said wheels may travel, auxiliary tracks adapted to swing laterally, means carried by the carriage for swinging the auxiliary tracks into alinement with the stationary tracks whereby said wheels may travel on the auxiliary tracks, and adjustable means for leveling said tracks.

6. An automatically operable grave cover comprising in combination with a casket lowering device, a carriage forming a horizontal table, track wheels for supporting the carriage, main track sections on which said wheels revolve, auxiliary track sections normally folded at right-angles to the main track sections, means carried by the carriage by which as the carriage travels toward the auxiliary track sections the auxiliary track sections will be turned into alinement with the main track sections and extending over the casket lowering device to permit the wheels of the carriage to travel on the auxiliary track sections whereby the carriage will be brought to position over the casket lowering device.

ORA E. STEGALL.
